UNITED STATES PATENT OFFICE

WILLIAM E. WINE, OF TOLEDO, OHIO

CAR DOOR MECHANISM

Application filed March 23, 1928. Serial No. 265,469.

My invention relates to railway car door mechanisms for retaining in closed position hinged doors adapted to swing to open position under the influence of gravity to permit the lading of the car to be discharged.

5 The principal object of the invention is to provide strong, simple and efficient means for retaining car doors of this type in closed position.

10 A primary feature of the invention consists in providing, in combination with a hinged door movable to open position under the influence of gravity, means for supporting the door in closed position involving a plurality of members rigidly mounted on the door and car body respectively, a pivoted member having a portion engageable with each of said rigidly mounted members and means forming a pivotal support for said pivoted member, the said portion of the latter member cooperating with said rigidly mounted members so as to be in double shear, thus relieving the pivotal support of said pivoted member from strain incident to maintaining the door in closed position.

15 Another feature of the invention resides in constructing a railway car, having a door movable to open position under the influence of gravity, with door locking mechanism involving members rigidly mounted on the door and car body respectively and a movable member having a portion engageable with said rigidly mounted members for supporting the door in partially closed and fully closed position, the said portion of the movable member being in single shear when supporting the door in partially closed position and being in double shear when supporting the door in fully closed position.

20 A further feature of the invention consists in providing a railway car having a lading discharge door movable to open position under the influence of gravity, with a door locking mechanism comprising a plurality of members rigidly secured to the car body and door respectively, one of the said members having spaced portions for receiving therebetween a portion of the other of said members, movable means being employed for operating with the said portions of each of

the members to support the door in closed position.

Other features of the invention, residing in particular details of construction and combination of parts, will hereinafter appear and be pointed out in the claims.

55 In the drawings illustrating a preferred embodiment of the invention:

Figure 1 is a fragmentary side elevational view of a portion of one of the hoppers of a 60 railway car of a well known type, showing mechanism involving the invention applied thereto, parts thereof being in section.

Fig. 2 is a view similar to Figure 1 illustrating the manner of supporting the door in 65 a partial or preliminary closed position.

Fig. 3 is a fragmentary end elevational view of the construction shown in Fig. 1.

Fig. 4 is a fragmentary sectional view taken on line 4—4, Fig. 1.

70 In the drawings, 1 indicates the side sheet or wall of a car hopper and 2 is the hinged door for closing the hopper discharge opening in the usual manner, the door being preferably hingedly connected to the car body 75 to swing to open position under the influence of gravity. Secured to the outer face of the door is a door spreader or stiffening beam 3 of preferably channel form having its flanges projecting downwardly. The spreader extends transversely of the car and is rigidly connected to the sections of the door on opposite sides of the car center sill so as to cause the door sections to operate as a single 80 unit.

85 Although a portion of the door at one side only of the car is illustrated, it will be understood that the door construction on the opposite side of the car is identical; and while only one mechanism for supporting the door is shown, it will be appreciated that a similar device is mounted on the opposite side of the car so as to sustain the door in closed position at that point.

90 Rigidly secured to the door spreader adjacent its outer end is a door arm or member 4, the inner end of which is of angular form having flanges 5 and 6 respectively. The door arm is rigidly connected to the door and door 100

spreader by rivets 7 and 8 respectively passing through the flanges 5 and 6.

Intermediate its ends the door arm is offset as at 9 to pass around the outstanding flange 10 of the door, and projects outwardly beyond the side edge of the door to form an extension 11 having an aperture 12.

Rigidly mounted on the side sheet 1 of the hopper is a bracket or member 13, any suitable means such as rivets 14, 15 and 16 being employed for this purpose. The bracket 13 is fashioned with spaced portions 17 and 18 respectively, forming jaws which project outwardly beyond the plane of the closed door, the jaws being adapted to receive the extension 11 of the door arm. Apertures 19 and 20 are formed in the spaced portions 17 and 18 respectively which, when the door is in closed position, are in registering alignment with the aperture 12 of the door arm extension.

The distance between the inner surfaces of the jaws 17 and 18 progressively increases in the direction of opening movement of the door, and the respectively adjacent surfaces 25 of the door arm extension are so arranged that, when the door is in closed position, they are substantially parallel with the inner surfaces of the jaws.

It will be appreciated that should the parts 30 of the mechanism become distorted or should the door sag upon its hinges, due to the extreme service conditions to which railway cars are subjected, the divergence of the inner surfaces of the jaws 17 and 18 is such as to guide 35 the extension into proper relation therewith.

Interposed between the bracket 13 and the side sheet of the hopper is a movable door locking member 21, the latter being apertured as at 22 for receiving the inwardly extending boss or lug 23 of the bracket member 13. The diameter of the aperture 22 is greater than that of the boss 23 to permit a relative sliding movement between the locking member 21 and the bracket 13.

The locking member 21 is preferably of hook shape having a normally downwardly projecting portion 24 which is adapted to extend through the apertures 19 and 20 of the jaws and the aperture 12 of the door arm extension.

The outer surface 26 of the portion 24 of the hook is radial, being struck from the rivet 15 as a center, and the portions of the apertures 19 and 20 which cooperate with this surface of the hook are similarly curved. The inner surface 27 of the hook extension 24, and the cooperating portions of the apertures formed in the jaws and the door arm extension 11, are inclined with respect to line A—A, so that the extension 24 of the hook may readily pass through the respective apertures when it is rotated about the rivet 15 as a center. It will of course be appreciated that upon rotation of the hook to door sup-

porting position the extension 24 thereof forces the door tightly shut.

Due to the action of gravity tending to swing the door open from the closed position indicated in Figure 1, the hook extension 24, by cooperating with the apertures in the jaws and door arm extension, is in double shear and the pivotal support of the hook is relieved from all strain.

The lower portion of the face 27 of the hook 75 is relatively inclined and affords a ledge 28 for supporting the door in a position of partial or preliminary closure. Upon reference to Figure 2 it will be seen that, when supporting the door in this position, a portion of the aperture 12 in the door arm extension engages the ledge 28 and an opposite portion of the aperture 19, in the upper jaw 17, engages the outer curved surface 26 of the hook extension 24. This latter portion 80 of the hook is thus in single shear when supporting the door in partial closed position and the pivotal support 23 is relieved from strain.

In order that the door arm extension 11 90 may be readily inserted between the jaws of the bracket 13, a cam or dog 29 is pivotally connected by a rivet 30 to the hook for supporting the latter in an elevated position. Adjacent its upper portion, the bracket 13 is provided with a laterally projecting marginal flange 31, the upper surface of which is fashioned with a depression 32 for cooperating with the cam 29 whereby when the latter is rotated into engagement therewith the 100 hook is maintained in a position such that the door arm extension may be easily brought into cooperative relation with the jaws of the bracket 13. The cam, in addition to the function just ascribed thereto, may advantageously be used to lock the hook in a position corresponding to fully closed position of the door. For this purpose the bracket 105 is fashioned with an upwardly extending rib or flange 33 which is adapted to cooperate 110 with the curved face 34 of the cam.

While it is a comparatively simple matter to swing the door to a partially closed position, extreme difficulty may be experienced in effecting a complete closure of the door, 115 due to warpage of the door and its associated parts. Means is thus preferably provided wherein a mechanical advantage may be utilized to force the door from a preliminary closed position to a final closed position. In 120 the present embodiment of the invention this means is provided by forming the lateral flange 31 with an apertured extension 35, constituting a fulcrum for a removable lever (not shown). The lever may be inserted in 125 the aperture either from the top or bottom thereof and is disposed so as to engage with an integral lug or projection 36 formed on the outer end of the door arm extension 11. Upon rotation of the lever in the proper di- 130

rection, the door may be readily forced from the partially closed position illustrated in Figure 2 to the fully closed position illustrated in Figure 1.

5 When the parts of the locking mechanism are in the positions shown in Figure 1, the door may be permitted to swing into open position under the influence of gravity by rotating the cam 29 in a clockwise direction 20 through approximately 180° and then moving the hook in the opposite direction. Rotation of the hook to permit the door arm extension 11 to pass from between the jaws of the bracket 13, enables the cam 29 to further rotate until it assumes a substantially vertical position. After the door arm has been thus disengaged from the hook and the door has moved to open position, downward rotation of the hook is arrested by the curved 25 surface 34 of the cam coacting with the depression 32 of the bracket.

It will thus be seen that when it is desired to close the door, the door arm may readily be inserted between the jaws of the bracket

25 13. Upon movement of the door to closed position, the inner upper edge of the door arm extension 11 engages with the approach plane 37 on the outer surface of the hook extension 24, forcing the hook upwardly.

30 Continued closing movement of the door permits the hook to move downwardly so that the ledge 28 thereof engages a portion of the aperture 12 in the door arm to maintain the door in a position of partial closure.

35 After the door is thus supported the cam 29 is rotated in a counter-clockwise direction so that the hook may be forced downwardly to cause the door to move to fully closed position. If sufficient leverage can

40 not be obtained by the coaction between the portion of the aperture in the door arm extension and the inner face 27 of the hook, the removable lever hereinabove described may be employed to force the door to closed 45 position. After the hook has been thus rotated the cam 29 is moved into the position shown in Figure 1, securely locking the door in closed position.

I claim:

50 1. In a railway dump car having a lading discharge opening, the combination with a hinged door for closing said opening, the door being movable to open position under the influence of gravity, of door locking mechanism involving a plurality of members rigidly secured to the car body and door respectively, one of said members having portions spaced from each other in a direction 55 substantially normal to the hinge axis of the door for receiving therebetween a portion of the other of said members, and movable means cooperable with the said portions of each of the members for supporting the door in closed position, said means being movable

in a plane substantially normal to the plane of the door.

2. In a railway dump car having a lading discharge opening, the combination with a hinged door for closing said opening, the door being movable to open position under the influence of gravity, of door locking mechanism involving a member rigidly mounted on the door, a member rigidly secured to the car body having apertured portions spaced from each other in a direction substantially normal to the hinge axis of the door for receiving therebetween a portion of the member secured to the door, and movable means normally carried by the car body adapted to be inserted in the apertures of said spaced portions for cooperating with the member carried by the door to support the door in closed position.

3. In a railway dump car having a lading discharge opening, the combination with a hinged door for closing said opening, the door being movable to open position under the influence of gravity, of door locking mechanism involving a plurality of members rigidly secured to the door and car body respectively, one of said members having spaced portions for receiving therebetween a portion of the other of said members, each of said portions having apertures capable of being brought into substantial alignment when the door is in closed position, and movable means adapted to be inserted in said apertures for supporting the door in closed position.

4. In a railway dump car having a lading discharge opening, the combination with a hinged door for closing said opening, the door being movable to open position under the influence of gravity, of a member rigidly mounted on the car body having a portion projecting beyond the plane of the closed door in the direction of opening movement of the door, a member rigidly mounted on the door having a portion projecting outwardly beyond a side edge thereof, the member mounted on the car body having jaws adapted to receive the outwardly projecting portion of the member mounted on the door, movable means cooperable with the jaws of the one member and the outwardly projecting portion of the other member to support the door in closed position, and means for maintaining said movable means in a position whereby the latter will automatically engage said outwardly projecting portion to support the door when it is moved to closed position.

5. In a railway dump car having a lading discharge opening, the combination with a hinged door for closing said opening, the door being movable to open position under the influence of gravity, of a member rigidly mounted on the door having a portion projecting outwardly beyond the side edge thereof, a member rigidly mounted on the car body

- having jaws for receiving the outwardly projecting portion of the other of said members, the distance between the inner surfaces of said jaws progressively increasing in the direction of opening movement of the door, and means cooperable with the jaws of the one member and with the outwardly projecting portion of the other member for supporting the door in closed position, said means being 5
cooperable with said members in a manner such that the door will be forced to closed position as the means is being brought into cooperative association with said members.
6. In a railway dump car having a lading discharge opening, the combination with a hinged door for closing said opening, the door being movable to open position under the influence of gravity, of a member mounted on the door having a portion projecting outwardly beyond a side edge thereof, a bracket member rigidly secured to the car body having jaws for receiving the outwardly projecting portion of the door member, the inner surfaces of the jaws and the adjacent surfaces of the jaw cooperating portions of the door member diverging outwardly in the direction of the opening movement of the door, and a movable means adapted to be inserted in apertures in the jaws of the bracket member and jaw cooperating portion of the door member to support the door in closed position.
7. In a railway dump car having a lading discharge opening, the combination with a hinged door for closing said opening, the door being movable to open position under the influence of gravity, of a bracket member secured to the car body, a member rigidly mounted on the door, each of said members 35
being fashioned with apertures adapted to be brought into substantial alinement when the door is moved to closed position and means pivotally mounted on the car body having a portion cooperable with the apertures of both 40

- of said members for supporting the door in closed position, said portion of the pivotally mounted means being in double shear when in door supporting engagement with said members.
8. In a railway dump car having a lading discharge opening, the combination with a hinged door for closing said opening, the door being movable to open position under the influence of gravity, of a plurality of members rigidly mounted on the door and car body respectively, one of said members having portions overlappingly embracing portions of the other of said members, said 55

members rigidly mounted on the door and car body respectively, and a movable member normally carried by the car body and cooperating with both of said members for supporting the door in a plurality of positions of closure, the member mounted on the car body having spaced portions and the member mounted on the door having a portion adapted to be interposed between said spaced portion, said movable member being engageable with one of said spaced portions and the said interposed portion for supporting the door in a position of partial closure and the said movable member being engageable with both of said spaced portions and the interposed portion for supporting the door in fully closed position.

13. In a railway dump car having a lading discharge opening, the combination with a hinged door for closing said opening, the door being movable to open position under the influence of gravity, of a plurality of members rigidly mounted on the door and car body respectively, and a movable member having a portion engageable with said rigidly mounted members for supporting the door in partially closed position and in fully closed position, said portion of the movable member being in single shear when supporting the door in partially closed position and being in double shear when supporting the door in fully closed position.

14. In a railway dump car having a lading discharge opening, the combination with a hinged door for closing said opening, the door being movable to open position under the influence of gravity, of door locking mechanism for supporting the door in partially closed and fully closed position, said mechanism involving a fixed member and a movable member, one of said members being mounted on the car body and the other being mounted on the door, and means operatively interposed between the movable member and the part upon which it is mounted for maintaining it in a position corresponding to that assumed by said movable member when supporting the door in partially closed position.

15. In a railway dump car having a lading discharge opening, the combination with a hinged door for closing said opening, the door being movable to open position under the influence of gravity, of door locking mechanism for supporting the door in partially closed and in fully closed position, said mechanism involving a fixed member and a movable member, the latter being adapted to move to locked position under the influence of gravity, one of said members being mounted in the car body and the other on the door, means operatively interposed between the movable member and the part upon which it is mounted for maintaining it in a position corresponding to that assumed by it when supporting the door in partially closed posi-

tion, and means for locking the movable member when supporting the door in fully closed position.

16. In a railway dump car having a lading discharge opening, the combination with a hinged door for closing said opening, the door being movable to open position under the influence of gravity, of a plurality of members rigidly mounted on the door and car body respectively, a member pivotally connected to one of said members and engageable with the other of said members to support the door in a position of partial closure and in a position of final closure, said pivotal member being adapted to move under the influence of gravity into both door supporting positions of closure, and means operatively interposed between the pivoted member and the member to which it is pivotally connected for maintaining the pivoted member in a position corresponding to that assumed by it when supporting the door in a partial position of closure.

17. In a railway dump car having a lading discharge opening, the combination with a hinged door for closing said opening, the door being movable to open position under the influence of gravity, of a member rigidly secured to the door and a member pivotally mounted on the car body and cooperable with the member on the door for supporting the door in partially closed and fully closed position, and means operatively interposed between the car body and pivoted member for supporting the latter in a position corresponding to that assumed by it when supporting the door in partially closed position.

18. In a railway dump car having a lading discharge opening, the combination with a hinged door for closing said opening, the door being movable to open position under the influence of gravity, of a relatively immovable member and a pivoted member, one of said members being mounted on the car body and the other on the door, the said immovable member being fashioned with an aperture adjacent its outer end and said pivoted member having a portion adapted to extend through said aperture to support the door in closed position, and means operatively interposed between the pivoted member and the part upon which it is mounted for maintaining the pivoted member in an elevated position to permit a portion of the immovable member forming a part of the aperture end thereof to pass beneath said pivoted member thereby enabling the latter to thereafter extend through said aperture.

19. In a railway dump car having a lading discharge opening, the combination with a hinged door for closing said opening, the door being movable to open position under the influence of gravity, of mechanism for supporting the door in closed position involving a pivoted member and a relatively

- immovable member, one of said members being mounted on the car body and the other on the door, and means pivotally connected to said pivoted member and engageable with a 5 relatively immovable part of the car for locking the pivoted member in door supporting position.
20. In a railway dump car having a lading discharge opening, the combination with a 10 hinged door for closing said opening, the door being movable to open position under the influence of gravity, of mechanism for supporting the door in closed position involving a pivoted member and a relatively immovable member, one of said members being mounted on the door and the other on the car body, rigid means forming a pivotal support for said pivoted member, and cam means 15 pivotally connected to the pivoted member and overlying the outer face thereof for engaging said rigid means to lock the pivoted member in door supporting position.
21. In a railway dump car having a lading discharge opening, the combination with a 20 hinged door for closing said opening, the door being movable to open position under the influence of gravity, of a plurality of members rigidly mounted on the door and car body respectively, a member pivotally 25 connected to the member mounted on the car body and cooperable with the other of said members for supporting the door in closed position, and cam means pivotally connected to the pivoted member and engageable with the member rigidly mounted on the car body for locking the pivoted member in door supporting position.
22. In a railway dump car having a lading discharge opening, the combination with a 30 hinged door for closing said opening, the door being movable to open position under the influence of gravity, of a plurality of members rigidly mounted on the door and car body respectively, a member pivotally 35 connected to one of said members and cooperable with the other of said members for supporting the door in partially closed and in fully closed position, and means pivotally mounted upon the pivoted member and overlying the outer face thereof for supporting the pivoted member in a position corresponding to that assumed by it when supporting the door in partially closed position.
23. In a railway dump car having a lading discharge opening, the combination with a 40 hinged door for closing said opening, the door being movable to open position under the influence of gravity, of a plurality of members rigidly mounted on the door and car body respectively, a member pivotally 45 connected to said pivoted member and engageable with the member mounted on the door for supporting the door in partially closed and fully closed position, and means pivotally mounted on 50 said pivoted member and engageable with the member rigidly mounted on the car body for supporting the door in partially closed position.
24. In a railway dump car having a lading discharge opening, the combination with a 55 hinged door for closing said opening, the door being movable to open position under the influence of gravity, of an arm rigidly mounted on the door and having an apertured portion, a bracket rigidly mounted on the car body and having spaced apertured portions for receiving therebetween the apertured portion of the door arm, a member pivotally connected to said bracket and engageable with the apertured portions of the latter and the door arm for supporting the door in closed position, and cam means pivotally connected to said member for locking the latter in door supporting position.
25. In a railway dump car having a lading discharge opening, the combination with a 60 hinged door for closing said opening, the door being movable to open position under the influence of gravity, of an arm rigidly mounted on the door and having an apertured portion, a bracket rigidly mounted on the car body and having spaced apertured portions for receiving therebetween the apertured portion of the door arm, a member pivotally connected with the bracket and engageable with the apertured portions of the latter and of the door arm for supporting the door in a plurality of positions of closure, and means pivotally mounted on the pivoted member for maintaining it in a position corresponding to that assumed by it when supporting the door in partially closed position and for locking the pivoted member in fully closed position.
26. In a railway dump car having a lading discharge opening, the combination with a 65 hinged door for closing said opening, the door being movable to open position under the influence of gravity, of an arm rigidly mounted on the door and having an apertured portion, a bracket rigidly mounted on the car body and having spaced apertured portions for receiving therebetween the apertured portion of the door arm, a member pivotally connected to said bracket and engageable with the apertured portions of the latter and the apertured portion of the door arm for supporting the door in partially closed and fully closed position, said member being movable into both positions of closure under the influence of gravity, and means pivotally connected to said pivoted member, said means being engageable with the bracket for supporting the pivoted member in a position corresponding to that as 70 75 80 85 90 95 100 105 110 115 120 125 130

sumed by it when supporting the door in partially closed position and being engageable with the bracket for locking the pivoted member when supporting the door in fully closed position.

27. A car door mechanism for the hopper of a railway car involving, in combination with a door hingedly associated with the hopper, a plurality of brackets one of which is secured to the door and the other to the side of the hopper, a member movably mounted on one of said brackets and engageable with the other to support the door in closed position, and means movably carried by said member and engageable with the bracket upon which it is mounted for locking the member in door-supporting position.

28. A car door mechanism for the hopper of a railway car involving, in combination with a door hingedly associated with the hopper, an arm secured to the door and projecting beyond a side edge thereof, a member movably mounted on the side of the hopper adapted to cooperate with the arm to support the door in closed position, and means movably carried by said member and engageable with a relatively immovable part of the car for locking the member in door-supporting position.

29. A car door mechanism for the hopper of a railway car involving, in combination with a door hingedly associated with the hopper, an arm secured to the door, a bracket secured to the side of the hopper, a member adapted to engage the arm to support the door in closed position, and means movably carried by said locking member and engageable with the said bracket for locking the member in door-supporting position.

30. A car door mechanism for the hopper of a railway car involving, in combination with a door hingedly associated with the hopper, an arm rigidly secured to the door, a bracket secured to the side of the hopper, a member movably mounted on the bracket and engageable with the arm to support the door in partially closed and in fully closed position, said member being movable into engagement with said arm under the influence of gravity, and means for maintaining the said member in a position corresponding to that assumed by the latter when supporting the door in partially closed position, said means being movable with and with respect to said member and being adapted to be operatively interposed between the latter and the said bracket.

31. A car door mechanism for the hopper of a railway car involving, in combination with a door hingedly associated with the hopper, an arm rigidly secured to the door, a bracket secured to the side of the hopper, a member movably mounted on the bracket and engageable with the arm for supporting

the door in partially closed and in fully closed position, said member being movable into engagement with the arm under the influence of gravity, and means carried by and movable with respect to said member adapted to maintain the latter in a position corresponding to that assumed by it when supporting the door in partially closed position, said means being also adapted to prevent accidental movement of said member when the latter is supporting the door in fully closed position.

32. A car door mechanism for the hopper of a railway car involving, in combination with a door hingedly associated with the hopper, an arm rigidly secured to the door, a bracket secured to the side of the hopper, a member movably mounted on the bracket and engageable with the arm to support the door in partially closed and in fully closed position, said member being movable into engagement with the arm under the influence of gravity, and means movably mounted on said member and adapted to cooperate with said bracket for maintaining the member in a position corresponding to that assumed by the latter when supporting the door in partially closed position, said means being also adapted to cooperate with the said bracket to prevent accidental movement of the said member when the latter is supporting the door in fully closed position.

In testimony whereof I affix my signature.

WILLIAM E. WINE.
